UNITED STATES PATENT OFFICE

99,113

DESIGN FOR A SHOE

Eli A. Cohen, Swampscott, Mass.

Application February 7, 1936, Serial No. 61,025

Term of patent 3½ years

To all whom it may concern:

Be it known that I, Eli A. Cohen, a citizen of the United States of America, residing at Swampscott, in the county of Essex and State of Massachusetts, have invented a new, original, and ornamental Design for a Shoe, of which the following is a specification, reference being had to the accompanying drawing, forming a part thereof.

The drawing is a perspective view of a shoe showing my new design.

The opposite side of the shoe presents substantially the same appearance as the side shown in the drawing, except for the absence of the strap end and buckle.

I claim:

The ornamental design for a shoe, substantially as shown and described.

ELI A. COHEN.
